FIG. 3.

Inventor

Thomas Downs
By Vernon C. Fadges
his Attorney

UNITED STATES PATENT OFFICE.

THOMAS DOWNS, OF SOMERSET, NEW JERSEY.

UP-DRAFT PROCESS OF AND MUFFLE KILN FOR FIRING.

Application filed January 25, 1927. Serial No. 163,479.

This invention is an improvement in up-draft process of and muffle kilns for firing which may be controlled while in progress of firing.

- 5 In the present forms of down-draft muffle kilns, there is a tendency to sulphur the ware, even under the exercise of the greatest skill and care in the progress of firing the kiln.
- 10 One object of my present invention is to overcome this tendency, by creating a more pure atmosphere within the kiln.

Another very important object of my invention is to provide a kiln which has all of 15 the advantages of the present kiln, and which overcomes the numerous disadvantages.

An important feature of this invention is the method of kiln drying the ware by 20 circulating heated air upward about the sides and through the center of the kiln and regulating said circulation.

A still further object is to provide a kiln that can be fired uniformly at top and bottom, which is very essential in firing large 25 pieces of ware, such as sanitary earthenware which is very susceptible to dunting when underfired.

Another object is to provide a kiln which 30 can be placed and replaced in a shorter period of time than the present well-known type of down-draft muffle kiln.

The chief reason for creating an up-draft muffle-kiln, instead of a down-draft kiln, is 35 to secure a more pure heat, whereas with the down-draft kiln it is more apt to sulphur the glaze on the ware. What is meant by a muffle-kiln is a separate lining within the body of the kiln with space between the 40 body and the lining.

Thus concerning the kiln, I have in mind to say:—

- (1) The kiln is round and has a cone-shaped stack on top.
- 45 (2) The kiln has a double crown with a space between for draft and cooling, and vent-holes in the upper crown and around the center stack, which runs from the bottom of the kiln to the top of the upper crown.
- 50 (3) There are flues running directly from the fire-boxes and side-walls to the center

stack which direct the sulphur and gas up into the cone-shaped stack which creates the greater part of the draft and cooling.

(4) The center stack is provided with a 55 damper control which enables the operator to advance the bottom heat or check it. In this way, the kiln can be fired evenly top and bottom, which is very essential in firing large pieces of ware, such as sanitary ware, 60 which are very susceptible to dunting if underfired, thus saving thousands of dollars' worth of ware.

(5) It is understood that this kiln will burn coal, gas, oil or any other fuel. 65

(6) Referring further to the up-draft of this muffle-kiln, this keeps the kiln free from bad atmosphere, such as found in down-draft kilns, which causes the glaze to become porous or sulphured, giving it a porous or boiled effect. 70

(7) The damper may be made with or without a hole in the center. This center hole allows passage enough to carry off any sulphur and gas without advancing too 75 much bottom heat.

(8) The fire-boxes are equipped with air-vents, admitting sufficient oxygen to create a pure heat.

A central stack is provided through the 80 center of the kiln, which extends upwardly from underground flues radiating from this central stack, which underground flues extend to peripheral fire-boxes, which supply the heat thereto. When the kiln is started in 85 its heating operation, a damper substantially closes the central stack which allows the heat to pass upward from the fire-boxes around the lining of the kiln, which is spaced from the main body thereof, and 90 through a double crown, the upper crown of which is provided with a plurality of openings through which the heat passes into a cone-shaped stack, which serves to carry it off. This creates a circulation of heat 95 around the sides and over the top of the kiln, but after it has been in operation for a period of time the damper is changed so that the draft through the central stack and through the flues located beneath the kiln, 100 will overcome that of the peripheral flues and will tend to direct the heated current of

air through the underground flues and central stack, which causes a more uniform distribution of heat over the bottom and sides of the kiln.

5 In the accompanying drawings:

Fig. 1 is a vertical section through the main body of the kiln;

Fig. 2 is a partial horizontal section taken on the line 2—2 of Fig. 1; and

10 Fig. 3 is a partial horizontal section taken on the line 3—3 of Fig. 1.

As shown in Fig. 1, the cork or foundation for the kiln is indicated by the numeral 1, upon which is supported the main body 15 portion 2 thereof. A plurality of fire-boxes 3 are provided about the periphery of the body portion 2, as clearly shown in Figs. 2 and 3. Any form of fuel may be used in these fire-boxes, such as oil, coal, etc. A 20 substantially-cone-shaped stack 4 extends upwardly from the body portion 2 of the kiln.

A lining 5 is spaced apart from the body portion 2 of the kiln by means of piers 6. 25 This lining 5 is seated upon the foundation 1, and is held in spaced-apart relation from the body portion 2. Extending inwardly from the lining 5 are a plurality of partitions 8, 9 and 10, which form underground flues therebetween. A tile floor 7 is mounted upon these partitions within the lining 5. The partitions are spaced apart, as shown in Fig. 3 to provide the radiating flues over the base of the kiln beneath the 35 tile floor 7. At their outer ends these underground flues extend to the bridge-walls 11 placed at the inner ends of the fire-boxes 3, which bridge walls are spaced apart from the lining 5, as shown in Fig. 1, so as to 40 permit communication from the fire-boxes to the underground flues.

Passage-ways 12 extend through the piers 6 and connect the vertical flues 13, as clearly 45 shown in Fig. 2. A central stack 14 rests upon the partitions 8 and floor 7 and extends upwardly, communicating at its lower end with the underground flues formed between the partitions 8, 9 and 10.

The flues 13, which extend upwardly between the piers 6, communicate at their upper ends with a space 15 formed between upper and lower crowns 16 and 17, respectively, which are spaced apart to form this space 15. The upper crown 16 is provided with a plurality of openings 18 therein, to allow the heat to pass from this space 15 into the cone-shaped stack 4, whence it is discharged into the atmosphere. A ventilating chimney 19 extends upwardly from the lower crown 17 in spaced apart relation around the central stack 14 to provide an open space therebetween, to allow sulphur (if any should seep in) to escape, so as to avoid injury to the glaze.

65 A damper control 20 is located at the top

of the central stack 14 for controlling the bottom heat, to advance or check the same. A small opening 21 is formed in the center of the damper control 20 to carry off any sulphur fumes that might be present in the 70 central stack 14. This damper control 20 is supported by means of rods 22 suspended from one end of a rock-arm 23, pivoted as at 24 to the cone-shaped stack 4. The outer end of the rock-arm 23 extends outwardly 75 through the side of the stack 4 and has a control-arm 25 connected thereto, for operating the damper. This control-arm 25 extends into convenient reach of an operator to allow easy manipulation of the damper 80 control.

In the operation of these muffle kilns, which are designed especially for firing sanitary earthenware, it is necessary to fire the kiln for several days before a sufficient temperature is obtained within the kiln to satisfactorily vitrify the ware. After the ware is placed within the kiln, the initial firing takes place. The damper control 20 is lowered over the end of the central stack 14, 90 which substantially prevents any circulation of heat beneath and through the center of the kiln. Instead, the circulation of heat is from the fire-boxes through the flues 13 on both sides of the piers 6 into the space 15 between the upper and lower crowns 16 and 17. The heat passes from the space 15 through the openings 18 in the upper crown 16 into the cone-shaped stack 4, from where it is discharged into the atmosphere. This circulation of heat evenly distributes it around the sides and over the top of the kiln and may be continued, as desired, after which the damper control 20 is opened, thus creating a circulation of heat through the 100 underground flues and central stack 14, which over-balances the circulation through the flues 13 and space 15 in the double crown. Thus, the heating air passes from the fire-boxes 3 behind the bridge-walls 11 at the back of the fire-boxes, down behind the bridge-walls and between the latter and the lining 5, to, and through the underground flues between the partitions 8, 9 and 10, to the center stack 14, as shown in Fig. 110 3. The heat passes through the latter and into the cone-shaped stack 4, whence it is discharged into the atmosphere.

This circulation of heat beneath the bottom and through the center of the kiln provides a uniform distribution of heat over the entire area of the kiln, thus preventing any burning of the ware, until the heat has become intense enough to vitrify the ware.

I claim:

1. The method of kiln drying ware in a kiln including circulating air upward about the sides and over the crown of the kiln, circulating air beneath the kiln and upward therethrough, and regulating and controlling 125

the relative circulations about and through the kiln.

2. The method of kiln drying ware in a muffle kiln including circulating air upward about the sides and over the crown of the kiln, circulating air beneath the floor of the kiln and upward through a central stack, and regulating and controlling the relative circulations about the side and through the central stack.

3. An updraft muffle kiln having a main body portion, a lining spaced apart from the body portion to provide circulating space therebetween for causing an upward circulation of heat about the lining, a stack for causing an upward circulation of heat from beneath the lining, and means for regulating and controlling the circulation of heat through the stack and about the lining.

4. An updraft muffle kiln having a main body portion, a lining spaced apart from the body portion to provide circulation space therebetween for causing an upward circulation of heat about the lining, a stack for causing an upward circulation of heat from beneath the kiln, and means for regulating and controlling the circulation of heat about the lining by regulating the circulation of heat through the stack.

5. An updraft muffle kiln having a main body portion, a lining spaced apart from the body portion to provide heat circulating space therebetween, a double crown communicating with said heat circulating space, and having an outlet, a floor having radial flues arranged therebeneath, a central stack extending upwardly from the floor through the kiln, a source of heat communicating with the radial flues, central stack, and heat circulating space about the lining for causing an upward circulation of heat about the lining and through the stack, and means for regulating and controlling the relative circulation of heat about the lining and through the central stack.

6. A muffle kiln having a main body portion, a lining spaced apart from the body portion to provide heat circulating space therebetween, a floor having flues arranged therebeneath, a fire-box arranged at the periphery of the body portion, and a bridge

wall arranged at the inner end of the fire-box in spaced apart relation from the lining to form a passageway between the fire-box to communicate with flues beneath the floor. 55

7. A muffle kiln having a lining, a double crown arranged thereabove, a central heat circulating stack extending upwardly through the double crown, and a chimney connected with the lower crown and spaced around the 60 central stack communicating with the interior of the lining.

8. A muffle kiln having a cone shaped stack at the top, a central stack, a double arched crown, a chimney spaced around the central 65 stack, and of less height than said stack, and means operating in connection with the upper end of the central stack for regulating and controlling the circulation of heat through the stack and crown. 70

9. A kiln of the character described including a base, a body portion extending upwardly from the base, a cone-shaped stack mounted upon the body portion, a lining arranged in spaced-apart relation from the body portion, forming flues therebetween, a plurality of peripheral fire-boxes arranged about the body portion of the kiln and communicating with said flues, a floor arranged in spaced-apart relation above the 80 base, a plurality of partitions formed between the floor and base to provide a plurality of underground flues therebetween, a central stack extending upwardly from the floor and communicating with said underground flues, a plurality of bridge-walls arranged at the inner ends of the fire-boxes in spaced-apart relation from the lining to form passageways between the fire-boxes and the underground flues, upper and lower 85 crowns formed in spaced-apart relation and forming a combustion chamber, said upper crown having openings formed therein for the escape of the products of combustion into the cone-shaped stack, a damper-control 90 in position to be seated over the top of the central stack to substantially close the same, said damper control having an opening therein for the escape of any sulphur fumes that might be present in the central stack. 95

In testimony whereof I affix my signature. 100
THOMAS DOWNS.
